ENERGIZING ELECTRICAL PRECIPITATOR

Harry J. White, Lawrenceville, N. J., assignor to
 Research Corporation, New York, N. Y., a corporation of New York

Application May 27, 1948, Serial No. 29,623

14 Claims. (Cl. 183—7)

1

The present invention relates to electric systems comprising an electrical precipitator for removing suspended particles from gases and a charging circuit for energizing the precipitator. In particular it relates to a charging circuit in which electrical power is supplied to an electrical precipitator in a series of evenly spaced, short duration current pulses of controlled characteristics, provision being made in the circuit for maintaining a supply of such power without interruption arising from the changeable and unpredictable load conditions which are commonly met with in electrical precipitators.

The usefulness of such a circuit depends to large extent upon the overall efficiency with which energy is transformed and transferred from one form to another and from one piece of equipment to another. This in turn depends upon the nature, relative rating, and arrangement of the equipment comprised in the circuit. It also depends upon the characteristics of the load, or loads, included in the system and the influence of the load upon the functioning of the energizing circuit.

An electrical precipitator for cleaning gases comprising spacially positioned and insulated complementary electrodes provides a very unpredictable electric load because, in its operation, mixtures of gas and suspended solid and/or liquid particles flow through the inter electrode spaces and these mixtures change in physical, chemical, and electrical characteristics due to changes at the origin of the mixtures, for instance, in the operating conditions in the furnace which may produce such mixtures. The gas may change in composition or temperature and the particles may change in composition, size, and concentration. At times of rapping the precipitator electrodes, the electrical conditions in the spaces between the electrodes, due to falling material, are greatly changed. Such changes alter the dielectric constant of the mixture, thus changing the capacitance of the precipitator; they bring about changes in the conductivity of the gases, and so change the electric power, due largely to corona discharges, required by the precipitator; and, without warning, spark-overs take place between the electrodes which temporarily short circuit the precipitator and initiate transients which will, unless prevented from doing so, travel back through the power supply circuit.

It is an object of the present invention to avoid these objectionable features and conditions by

2

providing a high efficiency circuit for the production of unidirectional current pulses and supplying the unidirectional pulses to the complementary electrodes of a precipitator through a unidirectional current passing device, such as a diode or a metal oxide rectifier.

Preferably the pulse energy is generated at relatively low voltage thus reducing equipment and operating costs and making it possible to transfer the pulse energy under low voltage conditions to the immediate vicinity of the precipitator. At the precipitator, a pulse transformer is provided which steps up the voltage of the pulses but which changes them practically not at all, otherwise. These pulses then flow through a one-way current transfer means to the precipitator. The one-way means causes retention in the precipitator, for use therein, of all energy that reaches it. This makes for economical operation, suppresses transients, and provides conditions which permit the charging circuit to function in an orderly and desired manner. The duration and peak value of the pulses can be largely controlled, conditions which have much to do with the efficiency of the operation of the precipitator. Use of a pulse transformer is not essential but is preferred in energizing precipitators at high potentials.

The term "pulses" is used herein to denote a succession of discrete increments of electrical energy separated by intervals of substantially greater duration than the duration of the increments of electrical energy.

Generally, the pulse charging system of the invention comprises a condenser, circuit elements including a series conductive impedance connecting a source of current to the condenser, circuit elements including a periodic circuit closing device, for example, a rotary gap switch, and an inductance connected in series with the condenser to provide a pulsing circuit, and circuit elements including a unidirectional current passing device connecting the pulsing circuit with complementary electrodes of an electrical precipitator. The pulse charging system may be energized with unidirectional current or with alternating current synchronous with the periodic circuit closing device of the system.

The invention will be more particularly described with reference to the accompanying drawing in which Figs. 1 to 5 are diagrammatic representations of five different charging circuits embodying the principles of the invention.

In the various figures like elements are indicated by like reference numerals.

In the drawing circuit of Fig. 1, 10 is a source of unidirectional current, and 11 and 12 are the discharge electrodes and collecting electrodes of an electrical precipitator, 13 is an inductance, 14 a rotary gap switch, 15 a condenser, 16 an inductance, 17 a pulse transformer and 18 a diode.

For the supply of pulses at a peak voltage of 60 kv. and a pulse rate of 240 per second to an electrical precipitator of approximately 5,000 cubic feet per minute capacity, D. C. power supply 10 may provide D. C. current at about 7200 volts. The following values of the circuit elements of Fig. 1 will provide the desired pulse energy at the precipitator:

Inductance	13: 43 h.
Rotary gap	14: 8 points, 1800 R. P. M.
Condenser	15: 0.048 mf.; 15 kv.
Inductance	16: 17 mh.
Pulse transformer	17: ratio 4.7
Diode	18: Eimac 250 R

The provision of a condenser 19 in shunt with the load is advantageous in providing further control of the voltage characteristics of the charging pulses and particularly for controlling the duration of potentials across the electrodes of the precipitator. The shunt condenser 19 is preferably much smaller in capacity than the charging condenser 15 and may be decreased in size and capacity with increasing pulse frequency.

The function of coil 16 may be filled by the provision of sufficient inductive leakage in pulse transformer 17.

The charging circuit of Fig. 2 includes a synchronous rotary gap switch 20 which functions as a commutating switch to distribute the energizing pulses in cyclic succession to a plurality of electrical precipitators through leads 21, 22, 23 and 24.

With a direct current supply 10 providing 13 kv., 1.8 Amp. direct current, the following values of the circuit elements will supply pulses of peak voltage 100 kv. at a rate of 480 per second providing 18 kw. for distribution to the four electrical precipitators:

Inductance	13: 3 h.
Rotary gap	14: 8 points, 3600 R. P. M.
Condenser	15: 0.15 mf.; 25 kv.
Inductance	16: 19 mh.
Pulse transformer	17: Ratio 7
Rotary switch	20: 8 points, 3600 R. P. M.

In the charging circuit of Fig. 3, the rotary gap switch 14 and the condenser 15 are interchanged. In the circuit of Fig. 3, a damping circuit, comprising series resistance 25 and diode 26 connected across the primary terminals of the pulse transformer 17, is provided. Since the diode 26 conducts whenever the voltage across the primary winding of the transformer becomes positive any transient voltages, which might arise in the primary due to sparking in the precipitator or other operating variables, are rapidly attenuated.

Fig. 4 shows a charging circuit including a plurality of pulse condensers 15a, 15b connected with D. C. power source 10 through inductance 13 and optional diode 28 and connected with inductances 16a, 16b and rotary gap switches 14 and 20 to be charged in parallel and discharged in series. The charging diode 28 makes it pos-

sible to vary the output frequency over a considerable range without changing the resonant frequency of the charging circuit including inductance 13 and capacity 15. A pulse transformer may be inserted in the circuit between inductance 27 and diode 18 as in Figs. 1 to 3. The values of the circuit elements will be selected in accordance with the principles illustrated in the illustrative values given for Figs. 1 and 2 to provide the desired pulse rate and peak voltage at the precipitator. The inductances 16a and 16b should be much greater than inductance 27, and inductance 13 should be much greater than inductances 16a, 16b.

In the charging system of Fig. 5, alternating current from motor-generator set 29 is stepped up to the desired voltage by transformer 30. The rotary gap switch 14 is driven in synchronism with the motor-generator set to close the pulsing circuit once each cycle when the A. C. voltage is zero. The pulse frequency will then be equal to the A. C. frequency and if the charging choke 13 and pulse condenser 15 are selected to be series resonant with the A. C. frequency the maximum pulse voltage will be πV^0 , where V^0 is the peak value of the A. C. voltage at the secondary of transformer 30.

If the transformer 30 is energized with line A. C. current, the rotary gap switch may be driven by a synchronous motor actuated by the line power. The function of the charging choke 13 may be filled by leakage inductance of transformer 30 if desired.

It will be seen that the construction and arrangement of the charging systems of the invention may be widely varied without departing from the principles of the invention.

By means of minor changes in the circuits a wide range of pulse frequencies, voltages and wave shapes can be provided, thus making it readily possible to adjust the energization of each precipitator installation to the particular conditions involved and obtain increased efficiency and smoothness of operation.

A number of precipitators or precipitator sections can be energized from a single charging circuit by commutation arrangements of the type shown in Fig. 2, without introducing any interaction of the precipitators with each other.

By the introduction of a pulse transformer into the charging circuits all of the circuit voltages may be kept relatively low, for example of the order of 5 kv. to 15 kv. for the direct current power supply and 10 kv. to 30 kv. for the pulsing circuit components. This makes it possible to locate the direct current power supply and the pulse generating circuit at any convenient location or locations, connections being made with relatively cheap power cable. The pulse transformer can be mounted close to or adjacent the precipitator and the high voltage output lead tied directly to the precipitator by a short direct connection.

The pulse generating circuit of the invention has the advantage that short circuiting the pulse transformer, as would occur in the case of sparking in the precipitator, does not result in any increase in power, as contrasted with the usual precipitator energizing circuits which, when the precipitator sparks, draw heavy currents and power and give rise to surges and electrode burning in the precipitator. These heavy sparking currents necessitate a large, power wasting, primary resistance in the high voltage transformer of ordinary energizing circuits in order to pre-

vent excessive precipitator arcs and current surges on the power line. The circuits of the invention require no such power wasting resistor, nor can any ordinary amount of precipitator sparking be harmful, although excess sparking is undesirable as it reduces precipitator efficiency.

This application is a continuation-in-part of my application Serial No. 774,142 filed September 15, 1947 and now abandoned.

I claim:

1. A charging system for an electrical precipitator comprising a condenser, circuit elements including a series conductive impedance means connecting a source of current to said condenser, circuit elements including a periodic circuit closing device and an inductance means connected in series with said condenser to provide a pulsing circuit, and circuit elements including a unidirectional current passing device connecting said pulsing circuit with the complementary electrodes of a precipitator.

2. A charging system for an electrical precipitator comprising a condenser, circuit elements including a series inductance means connecting a source of current to said condenser, circuit elements including a periodic circuit closing device and an inductance means connected in series with said condenser to provide a pulsing circuit, and circuit elements including a unidirectional current passing device connecting said pulsing circuit with the complementary electrodes of a precipitator.

3. A pulse charging system for an electrical precipitator comprising a condenser, circuit elements including a series inductance means connecting a source of unidirectional current to said condenser, circuit elements including a periodic circuit closing device and an inductance means connected in series with said condenser to provide a pulsing circuit, and circuit elements including a unidirectional current passing device connecting said pulsing circuit with the complementary electrodes of a precipitator.

4. A charging system for an electrical precipitator comprising a condenser, circuit elements including a series conductive impedance means connecting a source of current to said condenser, circuit elements including a periodic circuit closing device and an inductance means connected in series with said condenser to provide a pulsing circuit, and circuit elements including a unidirectional current passing device and a shunt capacity means connecting said pulsing circuit with the complementary electrodes of a precipitator.

5. A charging system for an electrical precipitator comprising a condenser, circuit elements including a series inductance means connecting a source of unidirectional current to said condenser, circuit elements including a periodic circuit closing device and an inductance means connected in series with said condenser to provide a pulsing circuit, and circuit elements including a pulse transformer and a unidirectional current passing device connecting said pulsing circuit with the complementary electrodes of a precipitator.

6. A charging system for an electrical precipitator comprising a condenser, circuit elements including a series conductive impedance means connecting a source of unidirectional current to said condenser, and circuit elements including a periodic circuit closing device, an inductance means and a unidirectional current passing device connecting said condenser with the complementary electrodes of a precipitator.

7. A charging system as defined in claim 6 wherein the circuit elements connecting the condenser with the complementary electrodes of the precipitator include an inductive coupler.

5 8. A charging system for an electrical precipitator comprising a pulse transformer, a pulsing circuit including a condenser, an inductance means and a periodic circuit closing device in series with the primary of the pulse transformer, 10 circuit elements including a series impedance means connecting a source of unidirectional electric current to said condenser, and circuit elements including a unidirectional current passing device connecting the secondary of the pulse 15 transformer to the complementary electrodes of the precipitator.

9. A charging system for an electrical precipitator comprising a pulse transformer, a pulsing circuit including a condenser, an inductance 20 means and a periodic circuit closing device in series with the primary of the pulse transformer, circuit elements including a series inductance means connecting a source of unidirectional electric current to said condenser, and circuit elements 25 including a unidirectional current passing device connecting the secondary of the pulse transformer to the complementary electrodes of the precipitator.

10. A charging system for an electrical precipitator comprising a pulse transformer, a pulsing circuit including a condenser, an inductance 30 means and a multiple rotary switch in series with the primary of the pulse transformer, circuit elements including a series impedance means connecting a source of unidirectional electric current to said condenser, and circuit elements including a unidirectional current passing device connecting the secondary of the pulse 35 transformer to the complementary electrodes of the precipitator.

11. A charging system for an electrical precipitator comprising a pulse transformer, a pulsing circuit including a condenser, an inductance means and a periodic circuit closing device in 40 series with the primary of the pulse transformer, circuit elements including a series impedance means connecting a source of unidirectional electric current to said condenser, and circuit elements including a diode connecting the secondary 45 of the pulse transformer to the complementary electrode of the precipitator.

12. A charging system for an electrical precipitator comprising a condenser, circuit elements including a series conductive impedance means 55 and a unidirectional current passing device connecting a source of current to said condenser, circuit elements including a periodic circuit closing device and an inductance means connected in series with said condenser to provide a pulsing 60 circuit, and circuit elements including a unidirectional current passing device connecting said pulsing circuit with the complementary electrodes of a precipitator.

13. A charging system for an electrical precipitator comprising a pulse transformer, a closed pulsing circuit including a condenser and a periodic circuit closing device connected in series with the primary of the pulse transformer, circuit elements including a series inductance means 65 connecting a source of unidirectional electric current directly to said condenser to form a second closed circuit, and circuit elements including a unidirectional current passing device connecting the secondary of the pulse transformer to the 70 complementary electrodes of the precipitator.
